UNITED STATES PATENT OFFICE.

MICHAEL E. DALY, OF CINCINNATI, OHIO, ASSIGNOR TO THE AMERICAN LAUNDRY MACHINERY COMPANY, OF CINCINNATI, OHIO, A CORPORATION OF OHIO.

DRUM CONTROL FOR WASHERS.

Application filed January 8, 1923. Serial No. 611,459.

This invention relates to improvements in mechanism for controlling the rotary drum of a washing machine.

The present invention relates to that type of washing machine in which there is provided a drum rotatably mounted within the casing, together with mechanism for automatically reversing the direction of rotation of the drum so as to give the drum alternate direct and reverse movement, as is well known in the art, and is an improvement upon the invention described and claimed in the prior patent to G. Binder, No. 1,160,687, granted November 16, 1915.

The objects of the present invention are to provide this type of washing machine with improved means for simultaneously disconnecting the rotating means of the drum and applying the brake thereto; to provide a single actuating member which is easily accessible to the operator for the purpose of effecting such operations; and furthermore to provide means readily accessible from the same position of the operator for causing manually controllable actuation of the drum in either direction so as to properly position the same for unloading and reloading after the automatic rotating and reversing means has been disconnected; all for the purpose of conveniently "inching" the drum into position with its door in registry with the casing door.

Other objects of this invention will appear from the following description and claims when considered together with the accompanying drawings.

Fig. 1 is an elevation of my improved machine taken from the right-hand end thereof; Fig. 2 is a detail sectional view of the brake mechanism; Fig. 3 is a front elevation; Fig. 4 is a detail sectional view of the right-hand end of my device taken on line 4-4 of Fig. 1; Fig. 5 is a detail sectional view of the header mechanism taken on line 5-5 of Fig. 6; and Fig. 6 is a detail sectional view of the header mechanism taken on line 6-6 of Figs. 3 and 5.

Casing 1 is suitably supported upon a standard or legs 2 and is provided with doors 3 through which access may be had to doors 4 provided upon drum 5 which is rotatably mounted within the casing. The means for rotating the drum comprises reversely driven belts 6 and 7 which extend about freely mounted pulleys 8 and 9 which are loosely

mounted about operating shaft 10. Intermediate driving pulley 11 is fixed upon shaft 10 and is adapted to be driven by either of belts 6 and 7 by shifting the same alternately back and forth in a manner to be described. 60 Pinions 12 provided upon the ends of shaft 10 mesh with gears 13 which in turn mesh with and drive main gears 14 which are fixed upon the shaft of drum 5.

Pulley 9 is referred to also as the worm pulley, since it is provided with worm section 15 to be operated therewith. Meshing with worm 15 is worm wheel 16 upon shaft 17, upon which there is mounted a cam member 18. This cam member is adapted to alternately engage rollers 19 which are mounted upon the forked end portions of rock arm 20 which in turn is pivotally mounted in the frame of the machine at point 21. Suitably mounted at point 22 there is provided also rock arm 23, the lower end of which is provided with lugs 24 for engagement in and cooperation with cut-out portions 25 of rock lever 20. The upper end of rock arm 23 is adapted to engage in cut-out portion 26 of belt-shifting 80 cam member 27 so as to give reciprocatory movement to the same during operation of the machine. This cam member is mounted upon and carried by belt shifting rod 28 which is suitably mounted in bracket 29 of 85 the machine frame for reciprocatory movement with the cam member. The other end portion of rod 28 has fixedly mounted thereupon bracket 30 through which extends pin 31 carrying belt-shifting bracket 32 which 90 has slots 33 and 34 through which the belts extend for transverse movement thereby. Thus it will be seen that during operation of pulley 9, rock arm 23 through the connections just described will effect a reciprocatory movement of cam member 27 and hence of rod 28 so as to produce a like movement of belt shifting bracket 32 and automatically shift belts 6 and 7 alternately into driving engagement with driving pulley 100 11. Belt 7 is sufficiently wide to at all times engage pulley 9 and hence ensure operation of the worm pulley without interruption. In this way, the direction of drive is automatically reversed so as to give reverse movement to the rotatable drum in the casing.

As a means of disconnecting this automatic reverse drive mechanism at the time when it is desired to stop the machine, I have provided elongated pinion 35 which is fixed- 110

ly mounted upon rod 28 and which has meshing engagement with segmental rack 36 carried by arm 37 which in turn is pivotally mounted about bracket 29. Arm 37 is adapted to be actuated by means of rod connection 38, the other end of which is manipulated by means of handle 39 which in turn is pivotally mounted at 40 upon bracket 41. Spring-pressed pin 42 is adapted to snap into engagement with recess 43 provided in one end portion of slot 44 so as to lock handle 39 in set position, this latch mechanism being adapted to be released by means of finger 44^a pivoted upon the handle for the purpose of releasing pin 42. Cap member 45 serves to secure bracket 29 to the main bracket or frame of the machine structure and supports also housing 46 for the brake mechanism. Mounted within brake housing 46 there is provided brake drum 47 which is bolted to pinion 12 at this end of the machine and is connected to shaft 10 by means of a spline connection indicated at 48. Housing 46 serves also to support stud 49 which carries at its inner end cam member 50 for engagement with brake shoes 51 which are in this way adapted to be thrust radially and outwardly against the brake drum against the tension of spring 52. The cam member 50 is actuated by means of suitable rod connections indicated in a general way by reference numeral 53 which in turn are connected with the same handle 39 which is used to actuate rack member 37. Thus I have provided a single means for releasing the automatic reversing mechanism and at the same time applying the brake so as to stop the drum.

Furthermore, I have provided a means which is adapted to be actuated by the operator so as to enable him to accurately position the drum with respect to the doors of the casing for unloading and reloading after the automatic operating means has been disconnected, as just referred to. This means comprises lever arm 54 which has forked end 55 engaging between fixed collar 56 on rod 28 and friction disc 57 on the end of pinion 35. Handle member 58 which is suitably mounted in bracket 59 has an arm 58^a which engages in recess or cut-out portion 60 of lever arm 54 so as to enable the operator to actuate the same for endwise movement of rod 28 after the belt shifting cam member has been disconnected from the operating mechanism of the machine.

Assuming the drum to be in operation, and assuming that the operator wishes to stop the machine, manipulation of handle 39 will, through the connections above described, cause rod 28 to rotate so as to disengage the belt shifting cam member from rock arm 23. Belts 6 and 7, as shown in the drawing, occupy idle positions, but should either of them occupy driving relation with respect to

driving pulley 11, such rocking movement of cam member 27 will automatically shift the belt to idle position by virtue of engagement of cam member 27^a with one of cam lugs 27^b. Such manipulation of handle 29 will at the same time apply the brake to stop the drum. To "inch" the drum into position with its doors in registry with the door openings of the casing, the operator, after opening the casing door, manipulates handle 58 to move rod 28 in either direction to rotate shaft 10 sufficiently to bring the drum to the desired position. This adjustment is of course effected after manipulating handle 39 to slack off the brake, and as soon as the drum door reaches registering position with the casing door, the brake is again applied by operating handle 39, after which handle 58 is at once operated to stop further drum drive.

The mechanism described is of particular value in connection with a washing or like machine in which a rotatable work carrying drum is reversely rotated during machine operation, such as for a washing treatment. Not only does the momentum of the drum increase the difficulty of "inching" to proper registering relation but, also, the load in these drums shifts around, and usually does so by sudden movements, requiring mechanism capable of quick and accurate control and operation if exact registration is to be secured.

What I claim is:—

1. In combination in a washing or like machine, a casing having a door, a cylindrical work holding drum therein having a door, automatic mechanism for rotating said drum alternately in opposite directions, controlling means for rendering said automatic mechanism effective or ineffective upon said drum, separate controlling means operable at will by the operator for producing rotation of said drum selectively in either direction, and brake means effective upon said drum and associated with said first named controlling means for conjoint operation therewith, whereby both of said means may be operated for stopping the drum with said doors in registering relation with each other.

2. In combination in a machine of the class described, a casing having a door, a cylindrical work holding drum therein having a door, automatic mechanism for rotating said drum alternately in opposite directions, controlling means operable at will by the operator for producing rotation of said drum selectively in either direction, brake means effective upon said drum for stopping the same, and operator operated controlling means for said automatic mechanism and brake means, whereby alternate operation of said two controlling means enables the drum to be released, rotated in either direction and braked to a stop at will, thereby securing accurate registration of said doors.

3. In combination in a washing or like machine, a casing having a door, a cylindrical work holding drum therein having a door, automatic mechanism for rotating said drum alternately in opposite directions, controlling means operable at will by the operator for producing rotation of said drum selectively in either direction, brake means effective upon said drum for stopping the same, a single operator operated controlling means for both said automatic mechanism and brake means, said two controlling means being located within easy reach of each other and an operator at the front of the machine and adapted by their alternate operation to conveniently secure registration of said doors.

In testimony whereof I hereby affix my signature.

MICHAEL E. DALY.
